I.F. Davidson, INVENTOR
BY *Victor J. Evans*

ATTORNEY

UNITED STATES PATENT OFFICE

ISAAC F. DAVIDSON, OF CENTRAL POINT, OREGON

SNOWPLOW

Application filed July 29, 1929. Serial No. 381,807.

The object of this invention is to provide a tractor propelled or tractor drawn plow including a scoop and a rotary element for receiving the snow from the scoop and discharging it under force in a lateral direction, and to provide particular adjustments such as those indicated below.

A further object is to provide a plow especially adapted to make the first cut on a grade or side hill.

10 A further object is to provide particular steering mechanism, and to effect vertical adjustment by the use of certain novel construction including a forward runner to be carried upon the surface of the snow.

15 A further object is to provide in advance of each runner, a small plow or the like adapted to cut a furrow, or to form furrows independently on opposite sides, of such depth respectively as may be required in order to effect levelling transversely of the machine.

In the drawings,

Figure 1 is a view of the plow and of the engine mounting portion of the structure, in 25 top plan.

Figure 2 shows the apparatus in side elevation.

Figure 3 is a vertical section through the inclosing means for the rotary device, the latter being in elevation.

Figure 4 is a vertical section on line 4-4 of Figure 3.

Figure 5 is a fragmentary side elevation illustrating one of the guide blades of the 35 scoop.

Figure 6 is a fragmentary top plan view illustrating the guide blade connected to the side of the scoop.

Figure 7 is a detailed sectional view illustrating the mounting of the guide blades to the scoop.

Figure 8 is a plan view, illustrating an attaching bracket for the guide blades, and

Figure 9 is a fragmentary perspective, illustrating a stop on one of the blocks.

Mention may first be made of the fact that altho packed snow of great depth requires removal of a few inches at a time, this type of apparatus is capable of doing the work rapidly in successive trips.

A main frame includes the side elements such as the member designated 10 in Figure 2 and similarly designated in Figure 1, and carried by said elements 10 is a platform or the like 11 adapted to mount an engine shown 55 conventionally and designated 12. The main shaft of the engine shown at 13 carries a pinion or gear wheel 14 meshing with gear wheel 15 on longitudinal shaft 16. This shaft mounts the rotary device constituting 60 a main element of the plow, and shown in detail in Figure 3. A key 16' in Figure 3 retains the rotary element in a given position with reference to the driving shaft.

Runners 18 are suitably secured as by 65 means of devices 19 shown especially in Figure 2, and braces 20 serve an obvious purpose in connection with the mounting and retention of the runners with reference to the main frame including elements 10.

A tractor hitch is designated 22, and the machine disclosed in Figures 1 and 2 would be propelled by the tractor, or may be drawn, by effecting connection at the forward end as shown at 24.

75 A forward frame includes the forwardly extending elements such as 25, and the vertically extending elements such as 26 and horizontal bar 27.

80 A scoop 28 is pivotally mounted at 29, with reference to the stationary portion of the structure, and a forward runner 30 adapted to be carried upon the surface of the snow shown at 31 in Figure 2, is pivotally carried by forwardly extending bars 32, the point or pivotal point of connection being illustrated at 33.

85 Bars 32 depend from a transverse bar or shaft 34, being adapted to swing with reference thereto, and slight relative movement is provided by means of slots 35, so that vertical adjustment of the runner 30 is not interfered with. Shaft 34 is mounted in brackets or the like 37, and vertical adjustment of the bars 32 and of the runner 30 is effected by means of a screw 38 passing thru the bar 27 and thru a threaded bore at 38'. A hand wheel 39 carried by the screw permits 95 of the adjustment of the latter, the lower end 100

of the screw being socketed or connected at 39' with the bars 32.

A steering lever is designated 40, and is held in any adjusted position by means of the 5 detents 41 cooperating with segments 42, the latter being mounted on bar 27. Lever 40 controls bars or the like 43, and the latter control blades or rudders 44 mounted for movement with reference to vertical axes 45.

10 Each blade 44 has associated therewith and adapted for movement with reference thereto in one direction only a tail or the like 46, these devices being in part under the control of tension elements 47, whereby movement about 15 the axes 45 is permitted, in one direction, and return to normal position insured. Hinge connections 48 are shown in Figures 2 and 5 between the tail elements 46 and the vertical axial element 45 and projections 46' are provided on the blades 44 to move the tails 46 in one direction with the blades as shown in Figure 6, it being understood that when the blades are moved in one direction, as shown in Figure 6, one of the tails moves with the respective blade as shown in dotted lines, while the other tail remains parallel with the side of the scoop and when the blades are moved in an opposite direction the other tail moves angularly to the side of the scoop, while the 30 first tail remains parallel to the side of the scoop.

A housing for the upper portion of the rotary device, or wheel constituting the main feature of the plow, so far as disposition of 35 the snow is concerned,—is designated 50, and discharge openings or mouth portions for the housing are shown at 51 and 52. The former provides for say a four foot level snow, while the upper discharge opening 52 is used for 40 greater depths.

The main element of the wheel is designated 54, and channelled steel blades 55 are curved approximately as shown and are carried by the wheel, while beveled cutting blades 45 56 are connected or secured at 57, near the point of connection of the elements 55 to the wheel 54. The beveled cutting blades are likewise connected at 58 to the elements 55, and the latter serve to engage the snow and 50 eject it laterally of the path of travel of the machine.

Forwardly of each runner 18, I mount a device acting as a plow or the like, and adapted to serve as a leveling element, so that by 55 control of the plow, leveling means for the apparatus is provided, as the position of the plow and the trough or cut made thereby will largely determine the position of the runner on that side of the machine. Each of these 60 plows 60 is mounted on a pivoted bar 61, and the position of element 61 is controlled by vertically extending rods 62 adapted for adjustment manually with reference to a guiding element 63 mounted at each side of the 65 machine. Engaging devices are provided for

retaining vertical rods 62 in adjusted position, these being shown at 64, and each element 62 carries a handle or the like 65 permitting of convenient control of elevation on either side of the machine in the manner indicated.

What is claimed is:—

1. A snow plow including a sled having a power driven snow receiving and delivery means, a scoop pivoted to the forward end of the sled to collect and deliver snow to said means, a supporting rod carried by the sled, an arm journaled to the rod and extending forwardly over the scoop, a snow engaging element carried by the arm in advance of the scoop, and an adjusting rod carried by the scoop and engaging the arm to vary the location of the arm relative to the scoop to increase and decrease the cuts of snow made by the scoop.

2. A snow plow including a sled having a power driven snow receiving and delivery means, a scoop pivoted to the forward end of the sled to collect and deliver snow to said means, vertically disposed guide blades hinged to the scoop, a steering means for varying the angles of the blades relative to the scoop, and tails for the blades and movable with the blades in one direction.

3. A snow plow including a sled having a power driven snow receiving and delivery means, a scoop pivoted to the forward end of the sled to collect and deliver snow to said means, vertically disposed guide blades hinged to the scoop, a steering means for varying the angles of the blades relative to the scoop, tails for the blades and movable with said blades in one direction, and tension means engaging the blades and tails.

In testimony whereof I affix my signature.

ISAAC F. DAVIDSON.
